CRANKSHAFT FOR TWO-STROKE ENGINES
WITH TWELVE CYLINDERS IN LINE

Jacques Steiger, Winterthur, Switzerland, assignor to Sulzer Frères, Société Anonyme, Winterthur, Switzerland

Application September 3, 1943, Serial No. 501,046
In Switzerland January 30, 1943

1 Claim. (Cl. 74—604)

1

The invention relates to a crankshaft for two-stroke engines with 12 cylinders in line having a uniform cranksetting of $12 \times 30^\circ$ and is characterised in that the two halves of the crankshaft differ from each other, that is to say the two halves of the crankshaft are not interchangeable and have the firing sequence of 1, 6, 11, 7, 3, 5, 10, 9, 2, 4, 12, 8, by means of which the critical speed of the 6th order is eliminated. In order to balance completely or in part the rotary moment of the 1st order of each crankshaft half, counterweights may be arranged on all the cranks.

Among known and possible crank orders in two-stroke engines with 12 cylinders in line, those with the twelve cranks all set at 30° , an arrangement which gives the best balanced crank effort diagram, are the ones which come into consideration first of all. Selected from this number are those with perfectly balanced masses and without free forces and moments of the 1st and 2nd order; and the preference goes to those having small internal moments, as great moments in the case of long engines such as the twelve-cylinder type might give rise to dangerous bending vibration.

In order to fulfil this latter requirement, each half of the engine must have its masses well balanced. The 6th order from the slipper pressures, which come into consideration as excitors of tilting vibration about the shaft axis, needs to be balanced as well as possible in each engine half, and this can be done with the known $30^\circ/90^\circ$ displacing of the 120° three-pointed stars in each engine half. Further, adjacent cranks should be set at as wide an angle as possible to each other, so that the journals lying between them are relieved of centrifugal forces from the eccentric rotary masses of the working cranks and the lower sections of the connecting rods. In view of their great length, shafts with twelve cranks are usually divided at the centre, the two halves being in general made identical and interchangeable.

The fulfilment of all the above conditions reduces the favourable cranksettings to a very small number. Unfortunately, all of these cranksettings with the shaft in two identical and interchangeable halves carry with them the disadvantage of a dangerous critical speed of the 6th order in the neighbourhood of the normal working speed corresponding to the usual piston speeds, a circumstance which is inadmissible in particular for propeller drives with variable speed. It would be possible to lower the critical

2

speed by means of additional masses and elasticities, but this would bring also the stronger lower orders down into the neighbourhood of the service speed. The danger zone of the sixth order then remains in a somewhat lower speed range, which makes it necessary to install a vibration damper.

An example of execution of the subject matter of the invention is represented diagrammatically in the accompanying drawings in which:

Figs. 1, 3 and 5 are diagrammatic views relative to a known form of crankshaft, Figs. 2, 4 and 6 are diagrammatic views relative to the improved form of crankshaft forming the subject matter of the present invention, Figs. 7, 8 and 9 are diagrams which will be more completely described hereinafter, Fig. 10 is an elevational view of a crankshaft embodying the present invention, Fig. 11 is an enlarged elevational view of the right-hand half of the crank shaft shown in Fig. 10, Fig. 12 is an end view of the half of the crankshaft shown in Fig. 11, Fig. 13 is a view similar to Fig. 11 of the left-hand half of the crankshaft shown in Fig. 10, and Fig. 14 is an end view of the half of the crankshaft shown in Fig. 13.

Fig. 1 shows the cranksequence of a known form of execution with a regular arrangement of the 12 cranks at 30° and the firing order of 1, 6, 8, 10, 3, 5, 7, 12, 2, 4, 9, 11. The two crankshafts halves are identical and interchangeable.

Fig. 3 illustrates the corresponding crank sequence of the 6th order with the cranks 1, 2, 3, 7, 8, 9 turned upwards and cranks 4, 5, 6, 10, 11, 12 turned downwards.

Fig. 5 gives the corresponding vector diagram with the strong resultant harmonic force 6th order R_6 .

Fig. 7 shows the computed form of the single-node oscillation, which serves to determine the vector diagram according to Figs. 5 and 6. The cylinders 1–6 to the left of node K are reckoned positive, and 7–12 to the right of the node negative. On account of the extremely favourable turning moment, twelve-cylinder engines with regular arrangement of the 12 cranks at 30° have light flywheels only, so that the oscillation node is in the neighbourhood of the centre of the engine.

Fig. 8 shows the distribution of the critical speeds and the height of the additional stresses T for the crank sequence according to Fig. 1 with the shaded, dangerous critical region of the 6th order in the proximity of the normal service speed B. Working of the engine within this critical zone is impossible owing to the high addi-

tional stresses, which would inevitably lead to the fracture of the crankshaft. This critical region is eliminated by the present invention, as can be seen from the further drawings.

Fig. 2 shows the new crank sequence 1, 6, 11, 7, 3, 5, 10, 9, 2, 4, 12, 8, or the same sequence reversed. The two regular three-pointed stars of each crankshaft section form the angle 30°/90° as in Fig. 1, yet the two sections are different and cannot be interchanged.

Fig. 4 reproduces the crank sequence of the 6th order corresponding to Fig. 2, with cranks 1, 2, 3, 10, 11, 12 turned upwards and cranks 4, 5, 6, 7, 8, 9, turned downwards.

Fig. 6 shows the new vector diagram, corresponding to Figs. 2 and 4 and again drawn on the basis of the form of vibration, computed according to Fig. 7. The cylinders 1-6 to the left of the node are again given the positive sign, and 7-12 to the right of the node the negative sign. The forces balance each other almost exactly, so that the resultant of the 6th order is nearly reduced to nought.

Fig. 9 gives the stress diagram thus obtained for the crank sequence in Fig. 2 according to the invention. The critical region of the 6th order has almost disappeared, the engine has a broad and practically vibration-free range between 70 and 130% of the normal speed.

With the use of a light flywheel and the resulting displacement of the vibration node into the neighbourhood of the middle of the engine, the critical region of the 12th order also disappears, since the vectors are all similarly directed and the two groups with unlike signs to the right and left of the node almost cancel each other. With regard to the 6th order, the favourable result of the invention is retained even when the oscillation node moves from the middle, for instance when a heavy flywheel is used.

Additional centrifugal masses may become necessary in order to move subordinate critical speeds into a lower speed range. The additional masses, instead of being put in the flywheel, may to advantage be placed on the working cranks themselves, as has been done in the example shown in Fig. 9, in order to set the critical region of the 9th order some 15% lower.

The counterweights on the cranks make it possible to decrease or eliminate completely the residual internal rotary moment of the 1st order in each crankshaft half. The internal vertical moment of the 2nd order is completely eliminated

in each shaft half in the crank arrangement chosen in Fig. 2. Counterweights on the cranks also diminish or exclude the centrifugal forces from the eccentrically rotating masses of the cranks and the lower connecting-rod halves and thus relieve the main bearings, which lie between the neighbouring angles with small intervening angles.

A physical embodiment of the crankshaft is shown in Figs. 10 to 14. The complete crankshaft is shown in Fig. 10 and comprises a left-hand half A and a right-hand half B connected together at C. The numbers of the cranks are indicated by Roman numerals.

The cranks of each half are uniformly set at 30° on center, and the cranks of the two halves are differently arranged, annularly, so that they are interchangeable. From the end views of Figs. 12 and 14 it will be noted that the order of the cranks consecutively around the axis of the crankshaft is that diagrammatically indicated in Fig. 2 and described above. Those figures also show that the annular disposition of the cranks of each half consecutively is 30° and 90°, alternatively, so that the critical speed of the 6th order substantially is eliminated, as described above.

I claim:

30 A crankshaft for two-stroke per cycle engines having twelve cylinders in line in which the cranks consecutively around the axis of the crankshaft uniformly are set at 30° on centers, a group of six consecutive cranks of one end of the crankshaft being differently arranged, angularly, from the group of six consecutive cranks of the other end of the crankshaft, so that said groups are not interchangeable, the firing order of the consecutive cranks from one end of the engine to the other being 1, 6, 11, 7, 3, 5, 10, 9, 2, 4, 12, 8 and the angular disposition of the cranks in the firing order being 30° and 90° alternately, whereby the critical speed of the 6th order substantially is eliminated.
